LIGHTING FIXTURE FOR RECREATIONAL VEHICLES, BOATS OR THE LIKE

Bruce G. Remington, Vicksburg, Mich., assignor to
Progressive Dynamics, Inc., Marshall, Mich.

Filed Dec. 29, 1969, Ser. No. 20,670

Term of patent 14 years

Int. Cl. D12—99; D26—02
U.S. Cl. D48—32

FIG. 1 is a front plan view of a lighting fixture for recreational vehicles, boats or the like embodying my new design;

FIG. 2 is a side elevational view thereof, the opposite side being a mirror image;

FIG. 3 is a right end elevation thereof;

FIG. 4 is a left end elevation thereof;

FIG. 5 is a front plan view of a second embodiment of my new design;

FIG. 6 is a side elevational view thereof.

The rear of the lighting fixture is plain and unornamented.

I claim:

The ornamental design for a lighting fixture for recreational vehicles, boats or the like, substantially as shown and described.
